S. E. GUINN

CIGAR LIGHTER

Filed June 15, 1923

UNITED STATES PATENT OFFICE.

SAMUEL E. GUINN, OF JOHNSON CITY, TENNESSEE, ASSIGNOR TO S. E. GUINN MANUFACTURING CO., OF CINCINNATI, OHIO, A CORPORATION OF NEW YORK.

CIGAR LIGHTER.

Application filed June 15, 1923. Serial No. 645,670.

This invention relates to a cigar lighter designed primarily to provide a portable structure adapted to be placed on a show case or other support, or to form a part 5 of the well known portable cigar stand adapted for individual or home use.

The lighter of the present invention is designed particularly for use of volatile fuel, delivered to the ignition point by means of 10 a wick, and ignited by a pyrophoric means actuated through the manipulation of the igniter casing, which casing is provided in part to act as a snuffer for the flame when closed and to trap a portion of the volatile 15 vapor from the fuel to be released at a subsequent ignition to insure the lighting operation.

The invention is illustrated in the accompanying drawings, in which:

20 Fig. 1 is a perspective view of the improved lighter.

Fig. 2 is a vertical section of the same.

Fig. 3 is a section on line 3—3 of Fig. 2.

25 Fig. 4 is a broken perspective view of the lighter, the igniter casing being shown open.

The improved lighter comprises a casing 1 serving as a receptacle for the fuel, as alcohol or the like, a wick tube 2 extending upwardly from the casing and in open communication therewith for the passage of a 30 wick 3.

An igniter casing is mounted above the wick tube 2, comprising a fixed section 4 of hollow formation, having a depending 35 threaded nipple 5 adapted to be screwed into the upper end of the wick tube 2 for supporting the igniter casing. The casing section 4 is provided with a wick guide 6 terminating in a conical end portion 7 for 40 operation with the snuffer as hereinafter explained. The igniter casing also includes a movable section 8 having depending ears 9 to permit hingedly connecting said movable section to the fixed section through a trans- 45 verse rod 10, on which within the casing is arranged a spring 11 with its free end engaging beneath the movable section 8 and serving to return the latter to closed position.

The movable section 8 is interiorly provided with a depending tube 12, adapted 50 when the section is closed, to cover the exposed portion of the wick 3 and also bear more or less snugly on the conical surface of the guide terminal 7, to form a seal to prevent 55 the vapor from the fuel escaping and

trapping the vapor within the tube 12 for a purpose which will presently appear.

Rotatably mounted in the forward portion of the fixed section 4 of the igniter casing is a shaft 13, on which is secured a disc 60 14 preferably of metal having a tangential arm 15, which extends forwardly through a slot 16 formed in the forward wall of the movable section 8 of the igniter casing, and projects beyond said igniter casing, as shown. 65 The disc 14 is provided with a lateral pin 17 connected by a spring 18 to the fixed section of the casing, whereby to maintain the disc 14 normally in an inoperative position, that is, with the arm 15 resting upon the upper 70 edge of the forward wall of the fixed section of the igniter casing, as clearly shown in Fig. 2.

To assist in arresting the arm 15 at all times in the same position, that is, preventing wear under the impact of the arm, the forward wall of the section 4 of the case, at the point of engagement therewith of the arm 15, is provided with an integral pillow block 4', the upper end of which receives a 80 hardened bearing pin 15', to receive the blow of the arm in the operation described.

The forward wall of the movable section 8 is provided with an operating hook 19, having a hook terminal 20 to normally underlie 85 the projecting portion of the arm 15, this hook having a lateral bar at the upper end pivotally connected at one end 21, to the movable section 8, the opposite end of the bar being free and normally resting upon a pin 22 projecting from the forward wall of the section 8, as shown more particularly in Fig. 1. Section 8 is provided with an operating handle 23 whereby said section may be 90 swung on its pivot 10 against the tension of 95 spring 11.

The pyrophoric igniter, here shown as of rod form, at 24, is slidably mounted in a tube 25 carried by the fixed section of the igniter casing and terminating at its upper end 100 in line with and below the shaft 13. The lower end of the tube depends below the fixed section 4 of the igniter casing, and is adapted to receive a rod 26 carried upon the upper end of the plunger 27 mounted in a bore 28 formed in a cylindrical web cast with and within the fuel casing 1, the bore 28 being of course closed against the fuel portion of the casing. The plunger 27 is 105 normally operated in the upward direction 110

by a spring 29 held in the reduced lower end of bore 28 and bearing against the plunger 27, and is manually retracted at will through a handle section 30, preferably of wire of U form to provide bearing width, which handle extends through a slot 31 in the adjacent wall of the fuel casing 1.

The operating member of the igniter is in the form of a serrated disc 32 fixed upon the 10 shaft 13 immediately above the tube 25, so that the pyrophoric material 24 is maintained in contact with the peripheral edge of said disc 32 at all times by the action of the spring 29.

Obviously, through manipulation of the handle 23, the movable section 8 of the igniter casing is turned on its pivot, and this action through the hook 19 serves to engage and raise the arm 15, move the disc 14 20 against the tension of the spring 18 and correspondingly move the igniter disc 32. The action continues until the hook end 20 rides off the end of the arm 15, whereupon the spring 18 operates to return the disc 14 and thereby the shaft 13 to normal position. In this movement of the shaft, the igniter disc 32 is moved rapidly over the end of the pyrophoric material and the resultant sparks 30 ignite the fuel at the wick 3. After the use of the light, the handle is released, the spring 11 acts to return the movable section of the igniter casing to normal position, the hook 19 being displaced by the end of the arm 15 and then returned to operative position below the arm, and the tube 12 acting to snuff or cut off the flame from the wick.

The tube 12 additionally serves to retain fuel vapor and to permit this vapor to escape adjacent the ignition point in the operation 40 of the device, whereby the ignition of the wick is rendered more certain and the proper operation insured through a single action of the pyrophoric material, thus avoiding the usual repetitions of the sparking action necessary to operate the usual igniter of this 45 type, and thus saving the material.

Through depressing the plunger 27 through the medium of the handle 30, to withdraw the rod 26 from the tube 25, fresh 50 pyrophoric material may be conveniently added without opening or disturbing any portion of the device other than that noted.

The igniter as a whole may be mounted upon a convenient base or desk or show case 55 application, or may form a part of the usual cigar storage and igniting outfit designed for home use, or may be made a stationary fixture at any place or places where it may be useful.

60 **Claims:**

1. In a cigar lighter, a fuel casing, an igniter casing arranged above the fuel casing, a wick extending from the fuel casing into the igniter casing, said igniter casing including a movable section, a pyrophoric ma-

terial tube carried by the igniter casing, means including a metal engaging member for causing a spark from said material, mechanism for setting said member for operation and releasing it to operate in the 70 opening of the movable section of the casing, and a snuffer tube carried by said movable section to serve as a vapor storage member when the igniter casing is closed.

2. A cigar lighter having an igniter casing made up of hingedly connected sections, pyrophoric igniter means arranged in one of said sections and including an arm projecting beyond the sections, and a hook carried by one of the sections to normally engage the projecting portion of the arm to lift said arm throughout a determinate distance in the opening movement of the sections, said hook being mounted to permit the hooked end thereof to pass said arm in the closing movement of the sections and to be operatively positioned beneath the arm by gravity.

3. A cigar lighter, comprising an igniter casing, having a fixed section and a movable section, a shaft mounted in the fixed section, an igniter disc on the shaft, an operating arm carried by the shaft and projecting through and beyond the casing, a gravity operated hook carried by the movable section of the casing to engage and move the arm for a portion of the opening movement of the casing, the relation of the centers of movement of said arm and the movable section of the casing causing the hook to release the arm prior to a full opening movement of the casing section, automatic means to return the arm to normal position following its release to thereby operate the igniter disc, and a tubular element 105 fixed in the igniter casing and terminating adjacent the igniter disc to receive pyrophoric material.

4. A cigar lighter, comprising a fuel casing, an igniter casing movably mounted above the fuel casing, igniter means including a sparking disc arranged within and automatically set and then operated in the movement of said igniter casing, a wick extending from the fuel casing into the igniter casing, a pyrophoric material tube carried by the igniter casing to receive pyrophoric material to cooperate with said igniter means, and an element slidably guided in the fuel casing to cooperate with said material in said tube and maintain endwise pressure thereon.

5. A cigar lighter, comprising a fuel casing, an igniter casing movably mounted above the fuel casing, igniter means including a sparking disc arranged within and automatically set and then operated in the movement of said igniter casing, a wick extending from the fuel casing into the igniter casing, a pyrophoric material tube

carried by the igniter casing to receive pyrophoric material to cooperate with said igniter means, a bore formed in the fuel casing in line with said material tube and 5 closed against said casing, and a spring pressed manually operable element mounted in said bore and including a rod to normally seat in said tube.

6. A cigar lighter, comprising a fuel casing, an igniter casing movably mounted above the fuel casing, igniter means arranged within and automatically operated in the movement of said igniter casing, a wick extending from the fuel casing into 15 the igniter casing, a pyrophoric material tube carried by the igniter casing to receive pyrophoric material to cooperate with said igniter means, a bore formed in the fuel casing in line with said tube and closed against 20 the fuel in the casing, the wall of the bore being slotted, a spring pressed plunger mounted in the bore, a rod carried by the plunger and adapted to seat in said tube to exert endwise pressure on the pyrophoric 25 material, and a manually operable member secured to the plunger and projecting through and guided in said slot, for manually withdrawing the rod from the tube 30 for the replacement of the pyrophoric material.

7. A cigar lighter, comprising a fuel casing, a wick tube projecting therefrom, an igniter casing mounted upon the upper end 35 of the wick tube and comprising a fixed section and a movable section, a wick guide in said fixed section formed with a sealing surface, a wick extending from the fuel casing through the wick tube and guide, spark producing means in the igniter casing 40 automatically set and then operated in the opening of the movable section of such casing, and a tube-like member carried by the movable section adapted to be sealed through

engagement with the sealing surface of the wick guide, the tube-like member being so 45 mounted on the movable section that as said section is opened to produce a spark the open end of the tube-like member is turned toward the spark generating point of the spark producing means, whereby the vapors 50 trapped in said tube-like member are brought immediately adjacent the sparking point for initial flame production to ignite the wick.

8. A cigar lighter, comprising a fuel casing, a wick tube projecting therefrom, an igniter casing mounted upon the upper end 55 of the wick tube and comprising a fixed section and a movable section, a wick guide in said fixed section formed with a sealing 60 surface, a wick extending from the fuel casing through the wick tube and guide, spark producing means in the igniter casing automatically set and then operated in 65 the opening of the movable section of such casing, and a tube-like member carried by the movable section adapted to be sealed through engagement with the sealing surface of the wick guide, the tube-like member being so mounted on the movable section that as said section is opened to produce a spark the open end of the tube-like member is turned toward the spark generating 70 point of the spark producing means, whereby the vapors trapped in said tube-like 75 member are brought immediately adjacent the sparking point for initial flame production to ignite the wick, the free end of the tube-like member moving wholly beyond the plane of the flame from the wick when the 80 movable section is open to permit uninterrupted access to such flame.

In testimony whereof I affix my signature.

SAMUEL E. GUINN.
